United States Patent Office

Des. 221,671

Patented Aug. 31, 1971

221,671

BASKETBALL GOAL

Jo Ann Hubert, 9146 Westview Drive,
Houston, Tex. 77055

Filed May 12, 1970, Ser. No. 22,935

Term of patent 14 years

Int. Cl. D21—03

U.S. Cl. D34—5

FIG. 1

FIG. 2

FIG. 3

FIG. 1 is a front perspective view of a basket for basketball games illustrating the design of the invention; FIG. 2 is a side elevational view of the same; and FIG. 3 is a top view of the same.

I claim:

The design for a basketball goal, as shown.
